F. MANKEY.

MOLDING.

No. 17,137.

Patented Feb. 22, 1887.

UNITED STATES PATENT OFFICE.

FREDERICK MANKEY, OF WILLIAMSPORT, PENNSYLVANIA.

DESIGN FOR A MOLDING.

SPECIFICATION forming part of Design No. 17,137, dated February 22, 1887.

Application filed November 13, 1885. Serial No. 182,753. Term of patent 7 years.

To all whom it may concern:

Be it known that I, FREDERICK MANKEY, of Williamsport, Lycoming county, Pennsylvania, have invented and produced a new and original Design for Moldings, of which the following is a specification, reference being had to the accompanying photograph, forming part hereof.

Upon the face of the molding appears a raised flat band, the opposite edges of which show each a series of scallops or convexities, B and C. Each scallop has one side, D, steeper or of greater curvature than the other side, E. The scallops B on one edge of the flat band are opposite the meeting points of the scallops B on the other edge. On the face of the flat band appear diagonal grooves or

channels E, relatively parallel, and extending between the meeting points of the scallops on respectively opposite edges of the flat band. 20

I claim--

The design for a molding, substantially as herein shown and described, which consists of a raised flat band, on the opposite edges of which appear convexities or scallops, each 25 scallop having one side steeper than the other side, and the scallops on one edge being opposite the scallops on the other edge, and the parallel diagonal channels E.

FREDERICK MANKEY.
